[57] **CLAIM**

The ornamental design for a beverage dispenser, as shown.

DESCRIPTION

FIG. 1 is a front, left perspective view of a beverage dispenser showing our new design;

FIG. 2 is a top plan view thereof;

FIG. 3 is a bottom plan view thereof;

FIG. 4 is a left side elevational view thereof;

FIG. 5 is a front elevational view thereof;

FIG. 6 is a right side elevational view thereof;

FIG. 7 is a rear elevational view thereof;

FIG. 8 is a front left perspective view of a beverage dispenser showing a second embodiment of our new design;

FIG. 9 is a top plan view thereof;

FIG. 10 is a bottom plan view thereof;

FIG. 11 is a left side elevational view thereof;

FIG. 12 is a front elevational view thereof;

FIG. 13 is a right side elevational view thereof;

FIG. 14 is a rear elevational view thereof;

FIG. 15 is a front left perspective view of a beverage dispenser showing a third embodiment of our new design;

FIG. 16 is a top plan view thereof;

FIG. 17 is a bottom plan view thereof;

FIG. 18 is a left side elevational view thereof;

FIG. 19 is a front elevational view thereof;

FIG. 20 is a right side elevational view thereof;

FIG. 21 is a rear elevational view thereof;

FIG. 22 is a front left perspective view of a beverage dispenser showing a fourth embodiment of our new design;

FIG. 23 is a top plan view thereof;

FIG. 24 is a bottom plan view thereof;

FIG. 25 is a left side elevational view thereof;

FIG. 26 is a front elevational view thereof;

FIG. 27 is a right side elevational view thereof; and,

FIG. 28 is a rear elevational view thereof.
